CLAIM

The ornamental design for an applied guide for stringed and fretted musical instruments, as shown and described.

DESCRIPTION

FIG. 1 is an isometric view of the applied guide for stringed and fretted musical instruments;
FIG. 2 is a front view thereof;
FIG. 3 is a rear view thereof;
FIG. 4 is a right view thereof;
FIG. 5 is a left view thereof;
FIG. 6 is a top view thereof;
FIG. 7 is a bottom view thereof;
FIG. 8 is an isometric view of the applied guide for stringed and fretted musical instruments, showing the guide sticker portion peeling;
FIG. 9 is an exploded view of the applied guide for stringed and fretted musical instruments; and,
